Primary Examiner — Richard Edgar*Assistant Examiner* — Jillian Mazzola(74) *Attorney, Agent, or Firm* — Nitin Kaushik(57) **CLAIM**

The ornamental design for a storage box as shown and described.

DESCRIPTION

FIG. 1 is a front, right and top perspective view of a storage box showing my design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and

FIG. 8 is a bottom plan view thereof.

FIG. 9 is an enlarged view of portion 9 shown in FIG. 1; and, FIG. 10 is an enlarged view of portion 10 shown in FIG. 1. The dash broken lines are included for the purposes of illustrating portions of the storage box that form no part of the claimed design. The dot-dash broken lines encircling portions of the storage box in FIG. 1 and shown in the enlarged views in FIGS. 9 and 10 form no part of the claimed design.

1 Claim, 10 Drawing Sheets(56)
